TIME ELEMENT ELECTROMAGNETIC DEVICE

Ludwig S. Walle, Lansdowne, Pa., assignor to
General Electric Company, a corporation of
New York

Application February 4, 1947, Serial No. 726,366

9 Claims. (Cl. 175—372)

1

My invention relates to improvements in time element electromagnetic devices and more particularly to improvements in electroresponsive devices such as relays, tripping devices and the like, which respond to an oscillating current above a predetermined magnitude in times which are inversely proportional to the magnitude of the current.

In order to obtain time delayed action in electromagnetic devices which respond to alternating current, many expedients have been adopted. Some of these have been based on the use of rotary motion embodying, for example, a drag magnet on an induction disk, the inertia of a heavy rotatably mounted member, centrifugal devices, and rotating vane mechanisms. Such devices are costly and more or less difficult to maintain or do not provide a suitable time current characteristic especially where a long time delay is required. Other devices have obtained time delay by movement of fluids or small solid particles through a narrow port after the manner of an hourglass or by movement of large solid particles in a tortuous path. Belonging to this group broadly are the dashpot devices usually employing oil which is very difficult to keep confined and which is erratic in performance because of its variation in viscosity with temperature. Some time element devices are of a thermal type based on expansion under heat, but these, generally speaking, do not provide either the time current characteristic desired or the force necessary in a direct tripping device for circuit breakers.

An object of my invention is to provide an improved time element electromagnetic device for oscillating current wherein the necessity for complicated movable structure and the use particularly of fluids and the like is eliminated. Another object of my invention is to provide an improved time element electromagnetic device which is responsive to oscillating current and which has a minimum number of movable parts and provides a suitable time current characteristic with sufficient force at the conclusion of the desired timing action to act satisfactorily as a direct tripping device for circuit breakers. Still another object of my invention is to provide a time element electromagnetic device for oscillating current wherein the desired timing action is based on the direct action of magnetic attraction and an opposing action of inductive repulsion which is controlled by a suitable heating effect. A further object of my invention is to provide an improved time element electromagnetic device for oscillating currents wherein the direct action of

2

magnetic attraction and the opposing action of inductive repulsion can be varied independently of each other to control the point where the direct action is effective to cause the operation of the device in the desired time. These and other objects of my invention will hereinafter appear in more detail.

My invention will be better understood from the following description when considered in connection with the accompanying sheet of drawings, and its scope will be pointed out in the appended claims.

In the accompanying sheet of drawings, Fig. 1 is a vertical side elevation, partly in section, of a hinged armature time element electromagnetic device embodying my invention; Fig. 2 is a front elevation of the embodiment of my invention shown in Fig. 1; Fig. 3 is a side elevation, partly in section, of a modification of the embodiment of my invention shown in Fig. 1 with independent adjustment of the magnetic attraction and inductive repulsion effects; Fig. 4 is a front elevation of the embodiment of my invention shown in Fig. 3; Fig. 5 is a side elevation, partly in section, of another embodiment of my invention in a reciprocating armature time element electromagnetic device with independent adjustment of the magnetic attraction and inductive repulsion effects; and Fig. 6 is a section on the line 6—6 of Fig. 5 looking in the direction indicated by the arrows.

In Figs. 1 and 2, I have illustrated an embodiment of my invention in an electromagnetic device having cooperating stationary and movable magnetic members 1 and 2, respectively. The stationary member 1 is in the form of a core which is suitably secured to a magnetic base member 3 on an extension 4 of which the movable magnetic member or armature 2 is pivotally supported at 5. As shown more clearly in Fig. 2, the core 1 is in the form of a cylindrical bundle of soft iron wires, and the armature 2 comprises three spaced magnetic portions 6, 7 and 8 which branch from a common backing member 9 of suitable magnetic material. The pivotal mounting of the armature 2 includes two nonmagnetic supporting elements 10 which are suitably secured to the armature portions 6 and 8 so as to straddle the extension 4 of the base member 3. The pivotal support or pin 5 passes through the nonmagnetic supporting members 10 and the base extension 4. The free ends of the armature portions 6, 7 and 8 are shaped so as to move freely to the attracted position in a notch 11 formed in the core 1 until the free end of the armature

engages the base 12 of the notch, as will be clear from Fig. 1. For energizing the magnetic members 1, 2 and 3, there is provided a winding 13 which when energized by an oscillating current above a predetermined magnitude tends to effect movement of the armature 2 toward the core 1.

As shown, the winding 13 is mounted around the core 1 on a suitable form such as a spool 14 which is preferably of nonmagnetic metallic material such, for example, as stainless steel. The flanges 15 of the spool 14 are preferably slotted as at 16 to restrict the formation of eddy currents. For adjusting the pickup of the device, that is to say at what magnitude of current in the energizing winding 13 the armature tends to move to the attracted position, there is provided an adjustably positioned support against which the lower end of the armature 2 abuts. As shown, this support comprises a screw 17 threaded into a nut 18 which is suitably secured to an angle bracket 19. This in turn is suitably secured to the magnetic base member 3. A lock nut 20 holds the screw 17 against movement when it is set for any desired pickup. With this arrangement, it is possible to vary the initial air gap between the free end of the armature 2 and the pole piece 12. With the structure so far described, movement of the armature 2 to the attracted position into engagement with the pole piece or notch 12 in the core would be substantially instantaneous. Mounted in the armature 2 to move therewith for controlling operations is a projecting element such as a pin 21 which may be arranged to operate a movable contact or to actuate the latch of a circuit breaker holding mechanism so as to trip the circuit breaker as is well known to the art.

In order to retard or delay the movement of the armature 2 to the attracted position, I provide, in accordance with my invention, means comprising a short circuited winding of positive temperature coefficient of resistivity such, for example, as a closed copper ring 22 which is movably mounted in inductive repulsion relation with the energizing winding 13 so as to exert on the armature an effect opposing the movement thereof toward the core 1 until the heating action of the current induced in the ring increases the resistance thereof sufficiently for the direct action of the energizing winding to overcome such opposing effect. For the maximum heating action, the central opening of the spool is made large enough to permit the ring 22 to move in the space between the cylinder of the spool and the core 1. In order that the inductive repulsion effect on the winding 22 may oppose the armature 2 directly, the two outside portions 6 and 8 thereof may be provided with nonmagnetic extensions 23. Also, to center the ring 22 for better freedom of movement relatively to the core 1, I preferably attach to the ring a guiding ring 24, shown in Fig. 1, of suitable nonmagnetic, noncurrent conducting, heat resistant material such, for example, as an asbestos ring. Further in order to keep the conducting ring 22 out of the magnetic center of the energizing winding 13 where the repelling action is minimum, I provide a relatively light biasing means such as a compression spring 25 which, as shown in Fig. 1, is positioned between the magnetic base member 3 and the ring 24. This spring 25 maintains the ring 22 in engagement with the armature extensions 23 and in the magnetic field due to the winding 13 at a position where the inductive repulsion action on the ring 22 is approximately maximum.

A movable short circuited winding such as the ring 22 always tends to move so as to enclose the minimum number of magnetic lines of force. Thus the ring 22 tends to hold armature 2 against stop 17 with a force great enough to predominate over the magnetic attraction thereof. However, it will be apparent that as the current decreases in the ring 22 in consequence of the heating thereof by the current induced therein, the flux in the magnetic circuit comprising the core 1, the base 3 and the armature 2 increases while the inductive repulsion action between the ring 22 and the energizing winding 13 decreases until finally the magnetic attraction between the armature 2 and its pole piece 12 and also between the armature and the base 4 is sufficient to overcome the inductive repulsion reversal of predominance of the opposite forces acting on the armature and move the armature to the attracted position. Thus, there is effected an accelerated action in consequence of the reduction of the repulsion action and the increase of the magnetic flux acting on the armature 2 which, of course, tends to move so as to enclose the maximum number of lines of predominance of the attractive over the opposing force. This accelerating force is easily sufficient to control contacts and can readily be made sufficient to effect the tripping of a circuit breaker. On the basis of the ring 22 being made of copper, its resistance is approximately doubled for a rise of 200° C. in temperature so that the current induced in the winding is approximately halved and the repulsion effect is rapidly decreased.

It will be clear from the foregoing that the time delay obtained for a given oscillating current in the winding 13 depends upon the initial position of the ring 22 relatively to the winding 13. Thus, when the center line of the ring 22 coincides with that of the winding 13, minimum time is obtained because the repelling action on the ring is substantially zero, whereas with the ring located at the end of the energizing winding 13, maximum time is obtained because in this position the inductive repulsion is at a maximum. It will be clear from the foregoing that any oscillating current, either alternating current, pulsating current or the like, may be used to energize the winding 13. The time current characteristic of a device such as that shown in Fig. 1 is, of course, inverse. In general, it has a fairly steep portion for small currents, but for larger currents, the change in the time of operation is not so rapid relatively to the increase in the current. The less steep portion of the characteristic coming as it does in the higher current range enables a more selective setting of relays and tripping devices particularly where it is desirable to arrange several of these in series relation in a power circuit so as selectively to isolate as little as possible of the circuit in the event of a fault.

In the embodiment of my invention shown in Figs. 3 and 4, the stationary magnetic member, comprising the core 1', the base 3' and its extension 4', is laminated with the outer plates flanged at 26 to provide ready means for mounting the device. The armature 2', like the core 1', is also laminated. The outside plates of the armature 2' are provided with extensions 27 which straddle the core 1' and come to rest in the unattracted position of the armature preferably against a resilient stop in order to minimize bouncing. As shown, this stop comprises rubber washers 28 mounted on the core 1' near the outer end there-

of. The energizing winding 18' is shown as a relatively heavy current capacity winding of the strap wound type.

In order to be able to adjust the position of the short circuited winding or ring 22' without changing the position of the armature 2' and also to obtain substantially instantaneous movement of the armature to the attracted position independently of the ring under severe current conditions in the nature of a short circuit, the core 1' is curved with its center of curvature on the pivotal axis 5' of the armature and the ring 22' is mounted for movement about this axis. For this purpose, the ring 22' is mounted on a generally U-shaped lever 29 which is supported on the pivot 5' and which has a backward extension 30. For adjusting the position of the ring 22' relatively to the armature 2', this lever 29 is provided with a forward projection 31 which abuts a milled cam 32 rotatably mounted on the armature. The face 33 of the cam 32 is suitably graduated, and a pointer 34 mounted on the outer end of the core serves for determining the setting of the ring.

For maintaining the ring 22' in a predetermined relative position and yet permitting movement of the armature 2' relatively to the ring under currents of short circuit magnitude in the winding 18', I provide a yielding connection between the armature 2' and the lever 29. As shown, this is a resilient connection such as a tension spring 35 which has one end attached to the backward extension 30 of the lever 29 and the other end adjustably attached to a projection 36 at the lower end of the armature. Thus at this other end, the spring 35 is secured by a screw 37 which can be turned to vary the tension in the spring.

For varying the pickup of the armature 2', I provide suitable means such as a relatively heavy counterweight 38 which is slidably positioned on a milled backward extension 39 of the armature projection 36. This weight 38 is generally U-shaped with channeled grooves 38' inside the bight embracing the edges and a portion of the milled surface of the extension 39 on each side thereof. By means of a spring 40, the upper side of each of the grooves 38' in the weight 38 is biased toward the milling on the extension 39 to hold the weight in any given position according to a suitably graduated scale 41 secured to the armature 2' so as to move therewith. Thus, by pushing up on the bottom of the weight 38 against the bias of the spring 40, the weight can be shifted to any desired position either to increase or decrease the pickup of the armature 2'. Then when released, the spring 40 holds the weight 38 in the position to which it was moved. In order to limit the extreme inner movement of the ring 22' relatively to the coil 18', the backward extension 30 of the lever 29 may be provided with a stop portion 42 which comes to rest against the back edge of the milled extension 39.

As in the embodiment of my invention shown in Fig. 1, the core 1' is notched at 11' to provide a suitable pole face 12' and the end of the armature 2' is suitably shaped to ride freely in this notch. In order to prevent the armature from sticking against the pole face 12', the inner face of the armature near the end thereof is provided with a nonmagnetic face plate 43.

While this embodiment of my invention operates in a manner generally similar to that of the embodiment of my invention shown in Fig. 1, there are some minor differences based on the

yielding connection between the ring 22' and the armature 2'. Thus, for example, the inductive repulsion effect of the ring 22' is exerted on the armature 2' by way of the lever 29 and the spring 35 so that whenever the force of attraction between the armature 2' and the magnetic structure comprising the core 1' and the base 3' exceeds this effect sufficiently to distend the spring 35, the armature will move to the attracted position. This stretching action of the spring will occur under heavy short circuit currents without any delay for heating the short circuited winding 22' or, in other words, waiting for the inductive repulsion effect to be reduced by such heating. Consequently, for currents of short circuit value regardless of the magnitude of the repulsion effect on the ring 22', the movement of the armature 2' is not delayed. For currents of overload values and the like which may reasonably be expected to disappear in many cases after a brief interval of time, the relative movement between the ring 22' and the armature 2' does not occur because there is insufficient force to produce stretching of the spring 35. Thus, in these cases, the time delay action is dependent upon the reduction of the magnetic repulsion effect in consequence of heating of the ring 22' so that the operation is the same as the embodiment of my invention shown in Fig. 1.

In the embodiment of my invention shown in Figs. 5 and 6, I have illustrated an electromagnetic device wherein the initial repulsion effect and the attractive effect on the armature can be independently adjusted. In this modification of my invention, the stationary magnetic member 44 is generally U-shaped with pole faces 45 at the end of each of the depending legs 46. Rigidly secured to the inside of the bight of the U-shaped member 44 substantially centrally of the legs 46 is a core member 47 having a pole face 48. Surrounding the core 47 and spaced therefrom is an energizing winding 49, which, as shown, is mounted on a spool 50 of suitable non-magnetic material such, for example, stainless steel. This spool is secured to the stationary magnetic member 44 on the inside of the bight by suitable means such as bolts 51. The flanges 52 of the spool and the lower portion of the legs 46 are notched, as shown, at 53 and 54, respectively, to minimize eddy currents.

Projecting through a central bore in the core 47 is a threaded rod 55 which serves as a support for a short circuited winding or ring 57. For holding an armature 56 in any desired position on the rod 55 so as to control the air gap between the armature and the pole faces and maintain the setting, the armature has a suitable friction holding nut 58. In order to minimize eddy currents, the armature is provided with a plurality of radial slots 59. For adjustably positioning the ring 57 relatively to the magnetic center of the energizing winding 49, the ring is provided with two diametrically aligned supports 60 extending from the inner circumference of the ring toward its center. The adjacent faces of these supports are tapped to fit the thread on the rod 55. In order to insure movement of the ring 57 relatively to the rod 55 when a handle 61 rigidly mounted thereon is turned, the core 47 is provided with two diametrically opposite slots 62, one of which serves as a guideway for a projection 63 secured to the ring 57. The other slot serves to maintain symmetry in the magnetic field, and the two slots also tend to break up eddy currents in the core. The core 48 may be pro-

vided with suitable graduations for setting the position of the ring relatively to the coil by noting where the end of the guiding projection 63 terminates relatively to the core.

In order to prevent unintended rotation of the rod 55 under shocks and the like, I provide suitable holding means such as a spring rod 64 which is arranged to engage a notch in the milled head of the handle 61. In order to reduce the chatter consequent upon cyclic variation in the current, suitable resilient means such as a rubber washer 65 may be mounted on the rod below the handle 61. For operating a contact mechanism or the latch of a circuit breaker, an operating member 66 is suitably mounted on the lower end of the rod 55.

In view of the description of the modification of my invention shown in Figs. 1 to 4, inclusive, the operation of the modification of my invention shown in Figs. 5 and 6, in so far as the inductive repulsion and magnetic attraction effects are concerned, will be apparent except for the matter of controlling the independent adjustments of the two effects. Thus, to control the air gap or magnetic attraction effect, the handle 61 is held while the armature is turned on the rod 55 to vary the air gap as desired. For controlling the position of the ring 57 relatively to the coil 49, the handle 61 is turned thereby rotating the rod 55 relatively to the ring 57 and thus raising or lowering the ring relatively to the magnetic center of the coil to vary the inductive repulsion effect.

While I have shown and described my invention in considerable detail, I do not desire to be limited to the exact arrangements shown, but seek to cover in the appended claims all those modifications that fall within the true spirit and scope of my invention.

What I claim as new and desire to secure by Letters Patent of the United States is:

1. In an electromagnetic device, a magnetic circuit having cooperating stationary and movable magnetic members, a winding for magnetizing said circuit when energized by an oscillating current above a predetermined magnitude to tend to effect movement of the movable member toward the stationary member, a short circuited winding of positive temperature coefficient of resistivity material movably mounted in inductive repulsion relation with said winding and having connections for exerting on said movable member an opposing force greater than the magnetic attractive force thereon to prevent movement of the member toward said stationary member until the heating action of the current induced in the short circuited winding increases the resistance thereof sufficiently to reverse the predominance of said forces.

2. An electromagnetic device having a core, an armature, an energizing winding around said core for attracting said armature when energized by an oscillating current above a predetermined magnitude, and a closed single turn winding of positive temperature coefficient of resistivity material movably mounted around said core in inductive repulsion relation with said energizing winding and having connections with said armature for exerting an opposing force thereon having predominance over the attraction of said armature until the heating action of the current induced in the single turn winding increases the resistance thereof sufficiently to reverse said predominance.

3. A time element alternating current electro-

responsive device having cooperating stationary and movable magnetic members in attractive relation, a tubular winding spaced around said stationary member for attracting said movable member when energized by current above a predetermined magnitude, the transverse area of the opening in said winding being materially greater than the cross sectional area of the stationary member, and a short circuited ring of positive temperature coefficient of resistivity material encircling said stationary member and movable in the space between the stationary member and the tubular winding under the inductive repulsion action thereof and having connections for preventing movement of the movable member toward the stationary member until the heating action of the current induced in the short circuited ring increases the resistance thereof sufficiently to render said repulsion action ineffective.

4. A time element alternating current electro-responsive device comprising a core, an armature, an energizing winding around said core and spaced therefrom for attracting said armature when energized by an oscillating current above a predetermined magnitude, and a closed single turn winding around said core movable in the space between the core and said energizing winding under the inductive repulsion action thereof and having connections for effectively opposing movement of the armature toward the core until the heating action of the current induced in the single turn winding increases the resistance thereof sufficiently to render said repulsion action ineffective.

5. An electromagnetic device having a core, an armature, an energizing winding around said core for attracting the armature when energized by an oscillating current above a predetermined magnitude, a closed single turn winding of positive temperature coefficient of resistivity material movably positioned around said core in inductive repulsion relation with said energizing winding, and connections between said armature and said single turn winding including a resilient element for causing the force of the repulsion effect on the single turn winding to oppose movement of the armature to the attracted position for a time dependent on the heating effect of the current in said energizing winding, said resilient element being adapted to yield to permit substantially instantaneous movement of the armature to the attracted position when the current in the energizing winding exceeds a greater predetermined magnitude.

6. An electromagnetic device having a core, a pivoted armature, an energizing winding around said core for attracting said armature when energized by an oscillating current above a predetermined magnitude, means for delaying movement of the armature to the attracted position including a closed single turn winding of positive temperature coefficient of resistivity material around said core in inductive repulsion relation with said energizing winding, means pivotally supporting said single turn winding for movement about the pivotal axis of said armature, and connections between said supporting means and said armature including an adjustable element for varying the position of the single turn winding relatively to the armature to control the delay in the attraction thereof, and a resilient element for yielding to permit substantially instantaneous movement of the armature relatively to the single turn winding when the current in said energizing winding

9 exceeds a greater predetermined magnitude. 7. An electromagnetic device having a core, an armature, an energizing winding around said core for attracting the armature when energized by an oscillating current above a predetermined magnitude, a ring of positive temperature coefficient of resistivity material positioned around said core in inductive repulsion relation with said energizing winding, and connections between said ring and said armature for opposing movement of said armature to the attracted position until the heating action of the current induced in the single turn winding increases the resistance thereof sufficiently to render the repulsive action of said ring ineffective, said connections including a resilient element for yielding to permit a substantially instantaneous movement of said armature to the attracted position when the current in said energizing winding exceeds a greater predetermined magnitude.

8. An electromagnetic device having cooperating stationary and movable magnetic members, a winding mounted on said stationary member to attract said movable member when energized by an oscillating current above a predetermined magnitude, a short circuited winding of positive temperature coefficient of resistivity material movably mounted in inductive repulsion relation with said energizing winding and having connections for exerting on said movable member a predominant force opposing the attractive force of the member toward said stationary member until the heating action of the current induced

5 in the short circuited winding increases the resistance thereof sufficiently to reverse the predominance of said forces, and means for independently adjusting the initial relative positions of said short-circuited winding and said armature with respect to the energizing winding to control said predominance reversal.

10 9. An electromagnetic device having a core, an armature, an energizing winding spaced around said core for attracting said armature when energized by current above a predetermined magnitude, a closed single turn winding of positive temperature coefficient of resistivity material movable on said core and having connections for 15 opposing the attraction of said armature, means including separate control elements for controlling the attraction of said armature and the inductive repulsion relation of said single turn winding with said energizing winding to oppose movement of the armature to the attracted position, said control elements being individually adjustable whereby independently to vary the attraction of the armature and the opposing effect of the single turn winding.
